DOUBLE ACTING DIESEL ENGINE

Karl Torjussen, Brooklyn, N. Y.

Application May 9, 1939, Serial No. 272,546

4 Claims. (Cl. 123—61)

My invention relates to improvements in double acting Diesel engines and particularly in the cylinder, piston and connecting rod arrangement of the same as well as in the scavenging system 5 providing scavenging air automatically without any separate air pump.

An important object of my invention is to provide a compact prime mover of minimum weight which can be used in air planes, busses, etc.

10 Another object of my invention is to provide a Diesel engine without a scavenging pump and having a minimum number of moving parts, thus insuring troublefree operation.

15 A further object of my invention is to provide a special piston construction and piston rod and connecting rod arrangements which will run cool and give maximum efficiency and be safe in operation and easy to take apart and overall.

20 Another object of the invention is to provide an air intake valve of special construction which is automatically operated by the pressure of the scavenging air thus eliminating the customary valves and valve operating mechanisms such as cam shafts, rods, springs.

25 Other objects and advantages of the invention will be apparent during the course of the following description.

30 In the accompanying drawings, forming a part of this specification, and in which like numerals are employed to designate like parts throughout the same,

Figure 1 is a transverse, vertical sectional elevation through the centre of a cylinder,

Figure 2 is a side elevation of a cylinder unit 35 and a longitudinal vertical section through another cylinder unit,

Figure 3 is a horizontal section along line 3—3 in Figure 1,

Figure 4 is a section along line 4—4 in Fig. 3,

40 Figure 5 is an enlarged section along line 5—5 in Fig. 3,

Figure 6 is a plan view of a special cylinder enclosure,

Figure 7 is a section through said cylinder end 45 closure, and

Figure 8 is a cross section of a piston from below.

In the drawings, wherein for the purpose of 50 illustration, is shown a preferred embodiment of my invention, the numeral 10 designates the cylinder head of the upper cylinder, see Figs. 1 and 2. The upper cylinder consists of one casting extending down to line 11. A similar cylinder block 12 forms the lower cylinder and extends up to line 13. Between the upper cylinder 10 and the

lower cylinder 12 there are two spacer elements 14 and 15, see Fig. 3. The entire cylinder structure is mounted upon the cast frames 16 and 17, one cylinder unit having one such frame on each side. The upper cylinders have ears 18 and the lower cylinders have similar ears 19 through which bolts 19a extend from the frames 16 and 17 upwards through holes in 15 and 16. By tightening nuts 20 the entire cylinder structure is clamped together tightly and at the same time 10 fastened to the frame. Suitable gaskets are, of course, placed between the cylinders 10 and 12 and the spacers 14 and 15. The frames 16 and 17 are mounted upon the bases 21 and 22 and the crankcase 23 is closed by covers 24. 15

The cooling water enters the lower cylinder at 25 goes through the openings 26, 27, 28 and 29 in the cooling jacket, see Fig. 3, and leaves the top cylinder through opening 30. The top cylinder also has a thermometer well 31, release valve 32 20 and starting air inlet at 33. The cylinder heads have fuel injection connections through openings 34 and 35.

The upper cylinder (10) has a piston 36 and the lower cylinder (12) has a piston 37 both of which 25 are working on a common piston rod 38. This piston rod 38 is preferably made with a cross head or hub 39 in the middle between the two pistons 36 and 37. The cross head 39 has a transverse shaft or pin 40 the ends of which are journaled in the bearings 41 and 42 of the two connecting rods 43 and 44. The lower ends 45 and 46 of the connecting rods 43 and 44 are fastened to the structure 47 which forms the lower bearing 48 and joins 43 and 44 rigidly into one connecting 35 rod acting upon crank 49 of the crank shaft 50 with crank shaft bearings 51 and 52. The ends of piston rod 38 have a cross pin 53 which is fastened to the piston by two clamps 54 and four bolts 55. On both sides of pin 53 are openings 56 leading to the inner recess 57 whereby air 40 may enter same to cool the piston, see Fig. 8.

The lower end of cylinder 10 and the upper end of cylinder 12 are closed by conical covers 58 and 59 which are split to facilitate mounting. 45 These covers 58 and 59 fit into recesses in the cylinder walls and have stuffing boxes 60 surrounding the hole 61 through which the piston rod 38 goes, see Figures 6 and 7.

The upper cylinder has exhaust ports 62 which 50 connect through pipe 63 to the main exhaust 64. The lower cylinder has similar exhaust ports 65 which connect through pipe 66 to the main exhaust 64. The scavenging air is taken in through opening 67 of valve housing 68, see Figures 3, 4 55

and 5. The valve consists of the valve housing 68 which on the inside has two walls 69 and 70 with circular holes through which the valve plates 71 and 72 may slide freely. The valve plates 71 and 72 are connected by a plurality of rods 73 and have shafts 74 and 75 at either end. These shafts 74 and 75 slide in bearing 76 and 77 in the elbows 78 and 79. Between the valve plates 71 and 72 and the bearings 76 and 77 are springs 80 and at the end of the stroke of shafts 74 and 75 are flexible stops 81 adjustable through bolt 82. The elbow 79 connects with channel 83 leading upward to the ports 84 below the piston 36 in the upper cylinder, and elbow 78 connects with channel 85 leading downward to ports 86 above the piston 37 in the lower cylinder, see Figures 1, 2 and 3. Other similar channels leads from ports 87 to the scavenging ports 88 in the upper cylinder, as shown in Fig. 1, and similar channels lead to similar ports in the lower cylinder.

The operation of my invention is similar to that of a two-cycle, double acting Diesel engine except in certain important particulars. The difference is mainly to be found in the scavenging system and in the general construction of a double-acting engine without crankcase compression and of such design as to permit easy assembly, good cooling of all parts, compact and sturdy construction, light weight and equal power in both cylinders.

The scavenging air enters through valve housing 68 and is sucked past valve plate 72 as indicated by arrows in Fig. 5. The air next passes through channel 85 and fills the space between the lower piston 37 and the closure 59 during the downward stroke of the piston. During the same time the upper piston 36 has compressed the air between it and the closure 58 because no air can escape past valve plate 71 which is held closed both by the compression from the upper cylinder and the suction from the lower cylinder working upon valve plate 72. As soon as the upper piston 36 uncovers ports 88 the compressed air will escape and sweep out the combustion gases from the upper cylinder. As soon as the pistons begin to travel upward again this procedure reverses. The lower piston 37 will now create compression and the upper piston 36 will make suction. These combined forces will move valve plates 71 and 72 into the opposite position and the lower cylinder will in turn be scavenged. The air intake valve is thus automatic in operation and requires no valve gear. By this method of scavenging no separate air pump is required and no air passes through the crank case thus keeping the oil clean and insuring a longer life of pistons and bearings.

The fact that the piston rod 38 only has a straight up and down motion minimizes greatly the wear upon pistons and cylinders. The special piston construction permits the scavenging air to cool the interior of the pistons thus insuring cooler operation. Due to the simplified scavenging system with fewer moving parts less power is required for this purpose and the overall efficiency of the engine is improved.

It is to be understood that the form of my invention, herewith shown and described, is to be taken as a preferred example of the same, and that various changes in the shape, size and arrangement of parts may be resorted to, without departing from the spirit of my invention, or the scope of the subjoined claims. It is obvious to one skilled in the art that my invention may be built with any number of cylinder pairs.

Having thus described my invention, I claim:

1. In a double acting internal combustion engine the combination of a lower cylinder with its head toward the crank shaft; an upper cylinder located in line with the lower cylinder but with its head in the opposite direction, said cylinders having a plurality of mounting ears; a piston in each cylinder; a common piston rod connecting the two pistons; a cross pin extending longitudinally to both sides from said piston rod; a crank shaft 10 journaled at one end of said cylinder; a forked connecting rod tying in said cross pin to said crank shaft; a plurality of spacer blocks placed between said two cylinders, said blocks having holes for mounting bolts; a frame structure 15 located on both sides of the lower cylinder; a plurality of mounting bolts whereby said cylinder blocks and spacers may be fastened to the frame; an end-closure closing each of the open ends of the two cylinders, and an automatic pressure operated air intake valve, one side of said valve being connected to the space between the piston and said closure in the upper cylinder, and the other side of the valve being connected to the corresponding space in the lower cylinder.

2. A double acting internal combustion engine comprising two opposed cylinders; a spacer structure located between the adjacent ends of said cylinders; a mounting frame; a plurality of mounting bolts holding said cylinders to the frame; two pistons one in each cylinder; a common piston rod connecting said pistons; a cross pin at the middle of said piston rod extending longitudinally to both sides out through the spacer structure; a crank shaft running longitudinally at one end of the cylinder structure; a forked connecting rod engaging said cross pin to the crank shaft; an automatic pressure and suction operated air intake valve; split end closures surrounding the piston rod and closing the open ends of said cylinders, and pipe connections connecting said air intake valve to ports located in the spaces formed between the pistons and the end closures.

3. A scavenging system for a double acting internal combustion engine, of the character described, comprising a flanged tubular valve structure having an air intake opening on one side; two inwardly extending radial walls in said valve structure one on each side of said air intake opening; a flanged elbow connected at each end of said valve structure; a bearing formed in each of said elbows; an adjustable stop in each end of said bearings; a valve structure comprising two discs fastened together with a plurality of rods; a valve stem extending from each valve disc and being slidably journaled in said bearings in said elbows; a spring surrounding said valve stems and being located between said valve discs and bearings, compression chambers formed in the cylinders by end closures, substantially as described, said cylinders having channels connecting said compression chambers to scavenging ports in the explosion chambers, and means connecting said valve structure to said compression chambers.

4. A scavenging system for a double acting opposed piston internal combustion engine such as described in claim 3 where said valve discs are of suitable thickness in relation to said inwardly extending radial walls and the spacing between said discs to give proper opening on the suction side while the compression side is closed.

KARL TORJUSSEN.
